CLAIM

The ornamental design for earphones, as shown and described.

DESCRIPTION

FIG. 1 is a front elevational view of the left earphone and a front elevational view of the right earphone showing the new design;

FIG. 2 is a rear elevation view of the right earphone and a rear elevational view of the left earphone;

FIG. 3 is a left side elevation view of the left earphone, in alignment with and overlapping the right earphone;

FIG. 4 is a right side elevational view of the right earphone, in alignment with and overlapping the left earphone;

FIG. 5 is a top view of the left earphone and a top view of the right earphone;

FIG. 6 is a bottom view of the left earphone and a bottom view of the right earphone;

FIG. 7 is a front elevational view of a right earphone and a front elevational view of the left earphone; and,

FIG. 8 is a perspective view of the left earphone and a perspective view of the right earphone.

The earphones are shown with a symbolic break in their length. The appearance of any portion of the earphones shown beyond the break lines forms no part of the claimed design. The symbolic break lines form no part of the claimed design.

1 Claim, 8 Drawing Sheets
